US00D859412S

(12) **United States Design Patent** (10) **Patent No.:** **US D859,412 S**
AlNasser et al. (45) **Date of Patent:** **** Sep. 10, 2019**

(54) **WEARABLE OR HANDHELD HYBRID SMART BARCODE SCANNER**

(71) Applicant: **Practech, Inc.**, San Francisco, CA (US)

(72) Inventors: **Khalid A. AlNasser**, San Francisco, CA (US); **Ibrahim O. AlGwaiz**, San Francisco, CA (US); **Mohammad A. Algassim**, Riyadh (SA)

(73) Assignee: **Practech, Inc.**, San Francisco, CA (US)

(**) Term: **15 Years**

(21) Appl. No.: **29/614,489**

(22) Filed: **Aug. 18, 2017**

(51) LOC (12) Cl. **14-02**

(52) U.S. Cl.
